CLAIM

(21) Appl. No.: **29/155,435**

The ornamental design for a multi-purpose cleaning tool
adaptive to a vacuum cleaner nozzle, as shown and
described.

(22) Filed: **Feb. 7, 2002**

DESCRIPTION

(51) LOC (7) Cl. **15-05**

FIG. 1 is a top frontal perspective view of a multi-purpose
cleaning tool adaptive to a vacuum cleaner nozzle showing
my new design;

(52) U.S. Cl. **D32/32**

FIG. 2 is a rear bottom perspective view thereof;
FIG. 3 is a top plan view thereof;

(58) Field of Search D32/31-33, 22,
D32/25; 15/322, 327.1-327.7, 329, 362,
393, 398, 400-401, 415.1-422.1

FIG. 4 is a front elevational view thereof;
FIG. 5 is a side elevational view thereof;

(56) **References Cited**

FIG. 6 is a rear elevational view thereof;
FIG. 7 is a bottom plan view thereof;

U.S. PATENT DOCUMENTS

FIG. 8 is a top frontal perspective view of a second embodiment
thereof;
